UNITED STATES PATENT OFFICE.

BERNARD H. ZIEHLER AND DON RAY ROWE, OF DAYTON, OHIO; SAID ROWE ASSIGNOR
TO SAID ZIEHLER.

LOCK.

1,212,599.

Specification of Letters Patent. Patented Jan. 16, 1917.

Application filed February 20, 1915. Serial No. 9,714.

To all whom it may concern:

Be it known that we, BERNARD H. ZIEHLER and D. RAY ROWE, citizens of the United States, residing at Dayton, in the county of 5 Montgomery and State of Ohio, have invented certain new and useful Improvements in Locks, of which the following is a specification, reference being had therein to the accompanying drawing.

10 This invention relates to locks, and more particularly to recording locks, which make a record pertaining to the manipulation of the bolt.

15 The object of the invention is to provide means to prevent the tampering with or fraudulent manipulation of a lock of this kind.

20 To this end it is a further object of the invention to provide means whereby it is necessary to completely move the bolt in one direction and to make a record each time the key is operated.

25 Further, it is an object of the invention to provide means for preventing two successive movements of the bolt-actuating devices in the same direction, thus causing a second record to be printed when there has been no actual movement of the bolt.

30 A further object of the invention is to provide means for preventing the device from being manipulated to wind off all the paper without making any record thereon, thereby permitting the lock to be subsequently operated without a record being 35 made.

It is also an object of the invention to provide a device of this character which will be very simple in its construction and operation; which will be of a strong, durable 40 character; which can be manufactured at a low cost; and which may be easily applied to a door.

45 In the accompanying drawings, Figure 1 is an elevation of one side of a lock with the casing in section; Fig. 2 is a vertical, sectional view taken through the casing near the edge of the door and showing the mechanism in elevation; Figs. 3, 4 and 5 are detail views of the bolt locking and key controlling devices showing the same in successive positions; Fig. 6 is a detail view of the full stroke mechanism for the platen; and Fig. 7 is a plan view of the clock showing the retaining device therefor.

50 In these drawings we have illustrated one

embodiment of our invention and have shown the same as comprising a main frame consisting of two plates 1 and 2 adapted to be secured to the opposite sides of the door and to support the various parts 60 of the mechanism. The plates constituting this frame may be secured to the door in any suitable manner, but, in the present instance, they are fastened one to the other by screws 3 extending through the door and 65 having mounted thereon spacing sleeves 4. The plate 1 is usually arranged on the inner side of the door and the mechanism carried by that plate is inclosed in a casing 5 which may be of any suitable character and is preferably movable in part or in whole to afford 70 access to the interior of the mechanism. The plate 2 is arranged on the outer side of the door and the mechanism carried thereby is supported between the two plates in 75 a recess or aperture formed in the door.

In the particular form of the mechanism here illustrated the bolt is shown at 6 and is slidably mounted on the plate 1 by means of pins 7 extending through horizontal slots 80 8 formed in the bolt. Suitable actuating devices are provided for imparting movement to this bolt and, in the present instance, these devices comprise two similar but independently operable actuating members 9 and 10 85 which are pivotally mounted on a common axis, and are provided with portions or arms extending on the opposite sides of said axis and having their upper edges inclined upwardly and outwardly from the axis to provide cam surfaces 12 and 13 which are so arranged that when movement is imparted to either of the actuating members in one direction the cam surface 12 of that actuating member which is moved will engage a pin 14 95 secured to the bolt 6 and move the bolt outward and when either of the actuating members is moved about its axis in the opposite direction the cam surface 13 of that actuating member which is moved will engage the pin 14 and move the bolt in the opposite direction. The actuating members are, as has been stated, separately movable, and, in the construction here shown, the members are 100 respectively connected with actuating knobs 15 and 16. These knobs are here shown as conventional round knobs, but it will be understood that the term is intended to include any kind of a manually operated device which may be substituted for these 110

knobs. The knob 15 is connected to the actuating member 9 by a shaft 17 extending through a suitable bearing 18, formed in the casing 5, and is rigidly secured to the member 9. This knob, which is arranged on the inner side of the door, is, usually, free to rotate and the bolt may be actuated by this knob at any time without the use of a key or other releasing device. However, as will 5 hereinafter appear, each operation of the knob produces a record. The knob 16 is connected with the actuating member 10 by means of a shaft 19 which is rigidly secured to the actuating member, extends through 10 the plate 1 and has a part extending into a hollow spindle 20 rigidly secured to the knob 16 and forming a support therefor, this spindle being journaled in the frame member or plate 2. The connection between the 15 shaft 19 and the spindle 20 is a slip connection, that is, it is such as to hold these parts against relative rotary movement but to permit them to be slipped apart when the plates 1 and 2 of the main frame are disconnected. This is accomplished, in the present 20 instance, by providing the shaft 19 with a longitudinal slot 21 and mounting a pin 22 in the hollow spindle 20 in a position to enter the slot in the shaft when the latter is 25 inserted in the spindle. To maintain the axes of the two actuating members 9 and 10 in alinement we have provided the shaft 19 with a portion which extends beyond the 30 face of the actuating member 10 and into a recess 23 formed in the end of the shaft 18, thus supporting the two members in their proper relative positions and permitting 35 them to have free rotary movement relatively one to the other.

40 The bolt is normally locked against movement in either direction, to prevent it being shifted by means other than the bolt-actuating devices. This is accomplished by providing the bolt in its upper edge with a 45 series of teeth 24 with which coöperate two oppositely extending pawls 25 and 26, both of which normally engage the teeth 24. Connected with the pawls 25 and 26 are arms 27 and 28 which preferably are mounted 50 on the same axes with the respective pawls and rigidly secured thereto. A spring 29 connects the arms and holds the pawls normally in engagement with the teeth 24. The outer ends of the arms of the two actuating 55 members 9 and 10 are cam shaped, as shown at 30 and 31, and the ends of the arms 27 and 28 are so arranged with relation to these cam shaped surfaces 30 and 31 that when one of the actuating members is 60 moved the outer cam surface, 30 or 31, will engage the adjacent arm, 27 or 28, and release the corresponding pawl before the cam surface, 12 or 13, engages the pin 14, thus releasing the bolt for movement in the desired 65 direction before the operative connec-

tion between the actuating device and the bolt is established. To prevent either actuating device being moved twice in the same direction, thus causing a record to be made, as will hereinafter appear, when there is no actual movement of the bolt, we have provided means which make it necessary for the actuating devices to move successively in alternate directions. To accomplish this the bolt is provided with recesses 32 and 33 so 70 arranged that when the bolt is in its retracted position the recess 32 will be in a position to receive the pawl 25 and when the bolt is in its projected or operative position the recess 33 will be in a position to receive 75 the pawl 26. Consequently, the arm, 27 or 28, as the case may be, will be moved beyond the position which it occupies when the pawl is in engagement with the teeth 24 of the bolt. This further movement of the arm 80 places it in the path of the upper cam surface, 12 or 13, of the actuating member and it forms a positive stop to limit the movement of the actuating member. It will be noted, therefore, that after the bolt has been 85 shifted to the limit of its movement in one direction the actuating device can not be again actuated in that same direction until the bolt has been moved toward the other opposite limit of its movement, thus causing 90 the arm of the pawl to be lifted up to its normal position.

The recording mechanism which coöperates with the devices here shown may be of various kinds but that which has been 100 chosen for the purpose of illustration consists of a clock 34 having a time registering device from which a record of the time can be taken. In the present instance, this device is of a known construction and consists of a printing dial 35 from which a record may be taken showing the time at which such record was taken. Coöperating with the dial to make a record therefrom is a platen 36 having a plunger or body portion 37 slidably mounted in a vertical bearing 38 and adapted to receive operative movement from the actuating device for the bolt. In the present instance, this operative movement is imparted to the platen by 105 means of a plate 39 which is operatively connected with the platen and is held normally in its elevated position by means of springs 40. The plate 39 extends transversely of the frame and is arranged beneath and adjacent to the two actuating members 9 and 10 which are provided along their lower edges with parts, such as the antifriction rollers 41, to engage the plate 110 and force the same downward when movement is imparted to either of the actuating members. These rollers are spaced such distances from the axes of the actuating members as will give the desired movement to the platen. The plate 39, which is here 115

shown as a substantially horizontal flat surfaced plate, may be of any shape or character which will enable it to coöperate in the desired manner with the actuating members. The plate 39 is rigidly secured to and guided by a pin or plunger 42 which is mounted in a guideway formed in the bearing block 38 which carries the platen. The connection between the plate 39 and the platen may be of any suitable character, but, as here shown, the connection is a cushioned one and the plunger 37 of the platen is provided with a recess in which is slidably mounted a stem 43, the upper end 15 of which is provided with an annular groove 44 to enable the same to be inserted in a slot 45 in the plate 39, thus forming a connection which causes the plate and the plunger 37 to move vertically in unison but 20 permits them to be readily separated. A spring 46 is mounted in the recess to resist the downward movement of the plunger 43. This construction permits the plate 39 to be moved a given distance upon each operation 25 of the device and the cushioned connection between the same and the platen not only gives a yielding pressure for taking the impression, but also accommodates the same to slight variations in distance. The record sheet or strip may be mounted in any suitable manner. In the present instance it 30 consists of a web of paper 47 mounted on a roll 48 on one side of the platen and extending about guides 49 and 50 to a receiving roll 52. Interposed between the record sheet and the form or dial is a suitable transfer device, such as the ink ribbon 53, which is wound upon spools 54 on opposite sides of the form and passes about guides 35 55 to position the same with relation to the form. Springs 56 pressing against the spools 54 hold the same normally against unwinding. The feeding of the ribbon may 40 be accomplished in any suitable manner, but, as it does not require frequent adjustment, we have, in the present instance, merely provided the spools with knurled knobs 57 by means of which the adjustment may be made by hand. Likewise, the paper 45 feed may be accomplished in any suitable manner but it is preferable that the paper should be fed forward automatically upon each operation of the platen and we have, therefore, provided a feeding mechanism 50 which is actuated upon each movement of the platen. To this end the receiving roll 52 is provided with a pinion 58 which meshes with a toothed rack 59 formed on a lever 60 pivotally mounted on that side of 55 the platen opposite the receiving roll. This lever 60 is connected with the platen to cause operative movement to be imparted thereto by the movement of the platen. This connection is formed, in the present instance, by providing the lever with a cam 60

slot 61 into which projects a pin 62 carried by the plunger 42 of the plate 39. If the feed mechanism were operated throughout the movement of the platen it would, in the present machine, result in the feeding of 70 too much paper and we have, therefore, so shaped the cam slot 61 that movement will be imparted to the lever during the first portion only of the movement of the platen. When the lever has been moved far enough 75 to feed the desired amount of paper the remainder of the cam slot has been moved into a position parallel with the line of movement of the platen so that the pin merely holds the lever in its depressed position without imparting further movement to it. In order that the receiving roll 52 may be actuated only upon the movement of the lever 60 in one direction the pinion 58 is connected to the roll by a pawl and 80 ratchet mechanism, as shown at 63.

We have provided means to prevent the paper feed mechanism being actuated by imparting short movements to the platen to feed all the paper off of the supply roll 90 48 thus allowing the recording mechanism to be operated without making a record. To accomplish this we have provided the platen with a full stroke device which prevents the same from returning to its normal position until it has been moved downward far enough to take an impression from the form. In the present type of machine this full stroke device comprises a pawl 64 pivotally mounted on the bearing block 38 100 adjacent to the plunger 42 and adapted to engage teeth 65 formed in the edge of the plunger. A spring 66 tends to move the nose of the pawl normally toward the teeth and the pawl is so arranged that upon the first downward movement of the platen it will engage one of the teeth and prevent the return movement of the platen. To release the platen from the pawl the latter is provided at its upper end with a finger 67 arranged 105 to be engaged by a projection or tripping block 68 secured to the plate 39. The relative positions of these two parts are such that the pawl will be tripped just as the platen completes its movement, thereby releasing the platen for return movement. To hold the pawl in its inoperative position during the return movement of the platen and after the tripping block 68 is moved out of engagement with the finger 67 a detent 69 110 is provided having a squared upper end, one corner of which is adapted to be moved into and out of the path of a projection 70 at the lower end of the pawl 64. A spring 71 tends to move the detent in a direction to move this corner or nose into the path of the projection. Consequently, as soon as the pawl has been moved into its inoperative position the detent will engage the projection 70 and retain the pawl in its inoper- 115 120 125 130

ative position during the upward movement of the platen. To release the pawl from the detent, for further operation, the platen is provided with a cam 72 so arranged that it will engage the detent and force the same out of engagement with the nose 70 of the pawl just as the platen reaches its uppermost position.

The actuating mechanism which is controlled from the outside of the door, that is, the actuating member 10 and the knob 16, are normally locked against movement and can be released only by means of a key. To accomplish this suitable key-controlled devices are provided which are of such a character that they not only control the movements of the bolt actuating mechanism, but also prevent the removal of the key from the lock except when the bolt is at one limit of its movement and the actuating mechanism is in its normally locked position. These key-controlled devices may be of various kinds, but those shown in the present embodiment of the invention are very efficient. As here shown the spindle 20 of the knob 16 has rigidly secured thereto a locking member which is here shown in the form of a disk 73 having a notch 74 adapted to receive a nose 75 of a locking arm or lever 76. This lever is pivotally mounted on the frame member 2 with its nose 75 normally in the notch of the locking disk and is acted upon by a spring 77 tending to move the nose 75 out of the notch of the locking disk. When the parts are in their normal positions, as shown in Fig. 3, the nose 75 is positively held in the notch of the locking disk, this being accomplished, by providing the arm 76 with a projection 78 arranged to ride over the edge of a cam disk 79 which is controlled by a key. The disk 79 is adapted to be rotated by the key, and is preferably rigidly secured to a rotatable part of the lock, such as a key barrel 80. The key and key barrel may be of any suitable construction but, in the present instance, we have employed the well known Yale type of lock and key. The shape of the cam disk 79 is such that when partial rotation has been imparted to the same by means of the key the higher portion of the cam will move out of engagement with the projection of the arm 76 and will permit the arm to move under the influence of the spring 77 to withdraw the nose 75 from the notch, thus releasing the bolt actuating device for operation from the outside of the door.

To insure the completion of a record and of the movement of the bolt, after the initial movement has been imparted thereto, we have provided means for retaining the key in the key barrel until these movements have been completed. To accomplish this the disk 79 is provided in its periphery with a notch

81 adapted to receive the end of a finger 82 pivotally mounted on the frame 1 and, in the present instance, on an axis coincident with the axis of the arm 76. The arrangement of the notch 81 and the finger 82 with relation to the cam surface of the disk is such that the finger will enter the notch when the cam surface has moved into a position to permit the releasing of the bolt-actuating device. Consequently, after the holder of a key has inserted the same in the lock and moved it far enough to release the bolt he cannot then withdraw it until he has completed the operations necessary to release the disk 79. After the key has been operated to release the parts and they have assumed the position shown in Fig. 4 the knob may be turned in either direction but after it has been started in one direction its movement in that direction must be completed before it can be returned to its normal position, this being accomplished by a full stroke mechanism 83 of a well known type. The finger 82 is held in its notch by the action of a spring and, in the present instance, the spring 77 is utilized for this purpose. To this end the finger 82 has connected thereto a second finger 84 extending alongside of the arm 76 and having a pin 85 which projects through a slot 86 in the arm 76 and affords means for connecting the spring 77 with the finger 84. This finger 84 also has a projection 87 which rides over the periphery of a cam 88, this cam being rigidly secured to the hollow spindle 20 of the knob. In the present instance, this same cam disk 88 is utilized as a part of the full stroke mechanism 83. That portion of the cam disk 88 adjacent to the notch 74 is of short radius so that the spring is free to move the finger 84 about its axis to cause the finger 82 to enter the notch 81 when the key is actuated. When the knob is turned to actuate the bolt the cam disk 88 forces the arm 84 downward against the tension of the spring 77 and thus moves the finger 82 out of the notch 81. At this time, however, the projection 78 of the arm 76 lies in front of the high portion of the cam disk 79, that is, the portion having the longer radius, as shown in Figs. 4 and 5, and inasmuch as the nose 75 of the arm bears against the periphery of the locking disk 73 the engagement of the cam disk with the projection 78 effectually holds the cam disk and, consequently, the key barrel against movement to their normal positions. However, the cam disk does have a slight movement before it comes into locking engagement with the projection of the arm and this movement is sufficient to move the notch out of alignment with the finger 82. Therefore, after the movement of the bolt has been completed and the bolt-actuating devices are being returned to their normal positions, thus moving the short radius

portion of the cam disk 88 into alinement with the projection 87 of the finger 84, the end of the finger 82 will engage the periphery of the disk 79 adjacent to the notch 81 and will, consequently, ride over the disk when the same is otherwise free for further movement. When the bolt actuating devices have completed their return movement the notch 74 of the locking disk 73 will have been moved into alinement with the nose 75 of the locking arm 76 and a spring 89, acting on the arm 76 through the cam 79, will cause the nose to enter the notch, thus locking the bolt-actuating devices. The movement imparted to the arm 76 by the cam is sufficient to carry the projection 78 out of the path of the high portion of the cam and to permit the cam, together with the key-barrel 80, to be returned to its normal position by the spring, which is preferably connected directly to the cam. This device effectually prevents any manipulation of the bolt without imparting a full movement thereto and thus causing a record to be made and it will be noted that by the use of the two retaining devices 82 and 78 the key barrel is held against movement to its normal position until the bolt-actuating devices have been returned to their normal positions, but at the same time the key barrel is free to return to its normal position as soon as the bolt-actuating devices have reached their normal positions. The movement of the key barrel in both directions is positively limited by a stop 90 arranged between two shoulders 91 and 92 formed on the cam disk 79.

In addition to printing the time on the record the mechanism is also adapted to print the identification of the particular key which was used to manipulate the lock. To this end the recording device has a second form 93 which is in the nature of a sliding bar arranged adjacent to the time disk and bearing type adapted to print initials, numbers or other identifying marks of the respective keys. These marks are arranged lengthwise of the type bar and are moved successively into printing position by the longitudinal movement of the bar. This movement may be imparted to the slide bar by the keys, as shown by key 102 in Fig. 2. The bar is held in its retracted position by a spring 94 and is provided with an enlarged end 95 arranged to be engaged by the keys when they are inserted in the barrel and in order that a different amount of movement may be imparted to the bar by the different keys the different keys are of different lengths. Consequently, each key will move the type bar in such a position that a different mark will be printed.

The clock mechanism may be supported in any suitable manner but, as here shown, comprises a rectangular frame consisting of up-

right posts 96. The two posts 96 adjacent to the frame member 1 are provided with openings to receive pins 97, onto or off of which the frame may be slipped when the casing 5 has been removed. To retain the clock frame against accidental displacement we have provided a spring-actuated latch 98 having a nose 99 adapted to extend through an opening 100 in the frame member 1 and to engage over the edge of the frame member and thus retain the clock in position. A finger piece 101 extends into a position in which it may be engaged and actuated to release the latch when it is desired to remove the clock.

The operation of the mechanism will be understood from the foregoing description and it will be apparent that the device is very simple in its construction and positive in its operation; that it is safe guarded against fraudulent manipulation by making it impossible to remove the key until a record has been made, or to otherwise manipulate the machine in such a way as to make a fraudulent record or to avoid making any record when the bolt is actuated. Further, it will be noted that the mechanism is all carried on the two parts of the frame and that the lock may be completely assembled at the factory. To attach the same to a door it is only necessary to provide the latter with an opening or recess to receive the parts carried by the frame member 1 and to permit the passage of the connecting bolts and the shaft 19. The two plates are then attached and placed in position on opposite sides of the door and again connected which completes the assembly and attaching of the lock. Neither the mechanism for actuating the bolt and the recorder or the means for preventing the removal of the key are broadly new in this application. An actuating device of this same type is disclosed and claimed in an application for patent filed by Bernard H. Ziehler April 25th, 1914, Ser. No. 834,518, and means for preventing the removal of the key are shown and described in an application for patent filed by Bernard H. Ziehler and James H. Dawley October 26th, 1914, Ser. No. 868,739. The present mechanisms are in the nature of improvements upon the devices of these earlier applications.

While we have shown and described one embodiment of our invention it will be understood that this has been chosen for the purposes of illustration only, and that we do not desire to be limited to the details of construction shown and described, for obvious modifications will occur to a person skilled in the art.

Having thus fully described our invention, what we claim as new and desire to secure by Letters Patent, is:—

1. In a lock; a bolt-actuating device there-

for, key-controlled locking means to prevent the actuating device from imparting movement to said bolt, and a device controlled by the locking means to prevent the removal of the key while said locking means is in an inoperative position and to release said key when said locking means assumes an operative position.

2. In a lock, the combination, with a bolt, 10 bolt-actuating mechanism, and a key-controlled device to lock said bolt-actuating mechanism against movement, of means controlled by said bolt actuating mechanism to prevent the removal of the key from said key-controlled device while said bolt-actuating mechanism is unlocked.

3. In a lock, the combination, with a bolt, 20 a locking device to prevent the operation of said bolt and a key to control the movement of said locking device into and out of operative position, of means controlled by the position of said locking device to prevent the removal of said key after said locking device has been moved into its inoperative 25 position.

4. In a lock, the combination, with a bolt, 30 actuating mechanism for said bolt, and a key-controlled device to lock said actuating mechanism against movement, of means to prevent the removal of the key from said key-controlled device after said actuating mechanism has been released and before said actuating mechanism has been operated.

5. In a lock, the combination, with a bolt, 35 means to lock said bolt normally against movement comprising a key barrel, a locking member, and a part carried by said key barrel to control the movement of said locking member, of means to prevent the return 40 of said key barrel to its normal position after it has been actuated and before said locking member has been moved into locking relation to said bolt.

6. In a lock, the combination, with a bolt, 45 bolt-actuating mechanism, a locking member movable into and out of operative relation to said bolt-actuating mechanism, and a key barrel, of a part carried by said key barrel to control the movement of said locking member.

7. In a lock, the combination, with a bolt, 55 bolt-actuating mechanism, a locking member movable into and out of operative relation to said bolt-actuating mechanism, and a key barrel, of a part carried by said key barrel to control the movement of said locking member, and means to prevent the return of said key barrel to its normal position when said locking member is in inoperative 60 position with relation to said bolt-actuating mechanism.

8. In a lock, the combination, with a bolt, 65 bolt-actuating mechanism, a locking member movable into and out of operative relation to said bolt-actuating mechanism, and a key

barrel, of a cam mounted on said key barrel and acting on a part of said locking member to control its movement into and out of operative position relative to said bolt-actuating mechanism.

9. In a lock, the combination, with a bolt, 70 bolt-actuating mechanism, a locking member movable into and out of operative relation with said bolt-actuating mechanism, and a key barrel, of a cam mounted on said key barrel and acting on a part of said locking member to control its movement into and out of operative position relative to said bolt-actuating mechanism, and means acting on 75 said cam and controlled by said bolt-actuating mechanism to control the return of said key barrel to its normal position after it has been actuated to release said bolt-actuating mechanism.

10. In a lock, in combination, with a bolt, 80 bolt-actuating mechanism, a locking member movable into and out of operative relation to said bolt-actuating mechanism, and a key barrel, of a cam mounted on said key barrel and acting on a part of said locking member 85 to control its movement into and out of operative position relative to said bolt-actuating mechanism, said cam having a notch, a finger mounted adjacent to said cam and adapted to be moved into and out of said 90 notch, and means under the control of said bolt-actuating mechanism to control the movement of said finger with relation to said notch.

11. In a lock, the combination, with actuating mechanism comprising a rotary part, 100 a locking member movable into and out of locking engagement with said rotary part, and a key barrel, of a member secured to and rotating with said key barrel to control the 105 movement of said locking member.

12. In a lock, the combination, with actuating mechanism comprising a rotary part, 110 a locking member movable into and out of locking engagement with said rotary part, and a key barrel, of a member secured to and rotating with said key barrel to control the movement of said locking member, a spring tending to return said key barrel to its normal position after it has been actuated, 115 and means controlled by said actuating mechanism and coöperating with the member on said key barrel to lock said key barrel against return to its normal position.

13. In a lock, the combination, with actuating mechanism comprising a rotary part, 120 and a locking member movable into and out of locking engagement with said rotary part, of a key-actuated cam acting on said locking member to control its movement into and out of operative relation with said rotary part.

14. In a lock, the combination, with actuating mechanism comprising a rotary part, 125 and a locking member movable into 130

and out of locking engagement with said rotary part, of a key-actuated cam acting on said locking member to control its movement into and out of operative relation with 5 said rotary part, said cam having a notch, a finger pivotally mounted adjacent to said cam and adapted to be moved into and out of said notch, and a part connected with said finger and controlled by said rotary member 10 to control the movement of said finger.

15. In a lock, the combination, with actuating mechanism comprising a rotary member, a part carried by said rotary member and having a notch, an arm pivotally 15 mounted adjacent to said rotary member and having a part adapted to be moved into and out of said notch to lock said actuating mechanism against movement, of a key-controlled cam having engagement with a part 20 carried by said arm and arranged to hold said arm normally in locking relation to said rotary member.

16. In a lock, the combination, with actuating mechanism comprising a rotary member, a part carried by said rotary member and having a notch, an arm pivotally mounted adjacent to said rotary member and having a part adapted to be moved into and out of said notch to lock said actuating 30 mechanism against movement, of a key-controlled cam having engagement with a part carried by said arm and arranged to hold said arm normally in locking relation to said rotary member, and means coöperating 35 with said cam and said arm to prevent the return of said cam to its normal position when said arm is in its inoperative position with relation to said rotary member.

17. In a lock, the combination, with actuating mechanism comprising a rotary member, said rotary member having a part provided with a notch, a cam rigidly secured to said rotary member, and a locking arm having a part adapted to enter said 45 notch, of a key-controlled cam mounted adjacent to said arm, said arm having a part to engage the periphery of said cam, said cam also having a notch, a pivoted finger adapted to be moved into and out of the 50 notch in said cam, and a second finger connected with the first-mentioned finger and mounted for engagement with the periphery of the cam on said rotary member, whereby the movement of said rotary member will 55 control the movement of the first-mentioned finger into and out of the notch in said cam.

18. In a lock, the combination, with actuating mechanism, a locking member movable into and out of operative engagement with 60 said actuating mechanism, and a key-actuated member, of a device actuated by said key-actuated member and coöperating with said locking member to prevent the return of said key-actuated member to its normal position during a portion of the time said

locking member is in its inoperative position with relation to said actuating mechanism, and other means coöperating with said device to prevent the return of said key-actuated member to its normal position during another part of the time that said locking member is in its inoperative position with relation to said actuating mechanism. 70

19. In a lock, the combination, with a bolt, and a locking arm, of a key-actuated cam to 75 control the movement of said locking arm into and out of its operative position, and means to control the return of said key-actuated cam to its normal position after movement has been imparted thereto. 80

20. In a lock, the combination, with a bolt, and a locking arm, of a key-actuated cam to control the movement of said locking arm into and out of its operative position, said locking arm and said cam having 85 parts coöperating to hold said cam against return movement when said arm is in its inoperative position.

21. In a lock, the combination, with a bolt, and a locking arm, of a key-actuated 90 cam to control the movement of said locking arm into and out of its operative position, said locking arm and said cam having parts coöperating to hold said cam against return movement when said arm is in its inoperative position, and other means coöperating with said cam to prevent its return to its normal position. 95

22. In a lock, the combination, with an actuating mechanism comprising a rotary 100 member, and a locking member adapted to be moved into operative relation with said rotary member when said actuating mechanism is in its normal position, of a key-actuated device to control the movement of said 105 locking member, said key-actuated device comprising a part coöperating with said locking member to prevent the removal of said key from said key-actuated device when said locking member is in its inoperative 110 position and movement has been imparted to the rotary member of said actuating mechanism, and other means to prevent the removal of said key when said locking member is in its inoperative position and before 115 movement has been imparted to said rotary member.

23. In a lock, the combination, with actuating mechanism comprising a rotary member having a part provided with a 120 notch, and a locking arm having a part to enter said notch, of a key-actuated device to control the movement of said locking arm, said key-actuated device comprising a part coöperating with said arm to hold said key-actuated device against return to its normal position after movement has been imparted to said rotary member, a finger coöperating 125 with said part of said key-actuated device to prevent the return of the latter to its nor- 130

mal position after said locking arm has been actuated to release said actuating mechanism and before movement has been imparted to said rotary member.

24. In a lock, the combination, with actuating mechanism, comprising a rotary member having a part provided with a notch, and a locking arm having a part to enter said notch, of a key-actuated device to control the movement of said locking arm, said key-actuated device comprising a part co-operating with said arm to hold said key-actuated device against return to its normal position after movement has been imparted to said rotary member, a finger co-operating with said part of said key-actuated device to prevent the return of the latter to its normal position after said locking arm has been actuated to release said actuating mechanism and before movement has been imparted to said rotary member, and means controlled by the movement of said actuating mechanism to move said finger into inoperative position.

25. In a lock, an actuating mechanism comprising a rotary member having a part provided with a notch, a pivoted locking arm having a projection, a key barrel, a cam actuated by said key barrel and co-operating with said locking arm when in one position to hold the locking arm in operative engagement with said rotary member and co-operating with said arm when in another position to prevent the return of said key barrel to its normal position, a pivoted finger adapted to be moved into and out of locking engagement with said cam to prevent the return of said key barrel to its normal position after it has been actuated, a second finger connected with the first-mentioned finger, a cam secured to said rotary member and acting on said second finger to control the position of the first-mentioned finger, and a spring tending to move said key barrel to its normal position.

26. In a lock, an actuating mechanism comprising a rotary member having a part provided with a notch, a pivoted locking arm having a part adapted to enter said notch and having a projection, a key barrel, a cam actuated by said key barrel and co-operating with said locking arm when in one position to hold the locking arm in operative engagement with said rotary member and co-operating with said arm when in another position to prevent the return of said key barrel to its normal position, a pivoted finger adapted to be moved into and out of locking engagement with said cam to prevent the return of said key barrel to its normal position after it has been actuated, a second finger connected with the first-mentioned finger, a cam secured to said rotary member and acting on said second finger to control the position

of the first-mentioned finger, and a spring interposed between said locking arm and said second finger tending to move the arm into its inoperative position and to move said second finger toward the cam on said rotary member.

27. In a lock, the combination, with a bolt, actuating mechanism for said bolt, and key-actuated devices to control the movement of said actuating mechanism, of means to prevent the removal of the key from said key-actuated device after the latter has been actuated and before said actuating mechanism has been operated, and means to prevent said actuating mechanism from being successively operated twice in the same direction.

28. In a lock, the combination, with a bolt, and actuating mechanism for said bolt, of means to prevent said actuating mechanism from making two successive operative movements in the same direction.

29. In a lock, the combination, with a bolt, and actuating mechanism for said bolt, of means controlled by the position of said bolt to prevent said actuating mechanism from making two operative movements in succession in the same direction.

30. In a lock, a bolt, a detent, said bolt having a notch arranged to receive said detent when said bolt is in one extreme position, an actuating member to impart movement to said bolt, and a part connected with said detent and arranged to extend into the path of said actuating member when said detent is in said notch.

31. In a lock, a bolt, and an actuating member having movement in two directions to move said bolt into its operative and its inoperative positions, two detents mounted adjacent to said bolt, said bolt having recesses arranged to be brought into alignment with the respective detents when said bolt is in its operative and inoperative positions, respectively, and parts connected with said detents supported normally out of the path of said actuating member and each adapted to be moved into the path of said actuating member when its detent enters the corresponding notch.

32. In a lock, a bolt having a series of teeth along one edge thereof, two spring-actuated detents adapted to engage said teeth to hold said bolt against movement in either direction, said bolt having a projection, an actuating member mounted for movement in two directions and having parts adapted to operatively engage said projection and impart movement to said bolt, and arms secured to the respective detents and arranged to be engaged by the respective parts of said actuating member before said parts engage the projection on said bolt.

33. In a lock, a bolt having a series of

teeth along one edge thereof, two spring-actuated detents adapted to engage said teeth to hold said bolt against movement in either direction, arms operatively connected with said detents, said bolt having a projection arranged between said detents, a pivoted actuating member having two cam surfaces on each side of its axis, one of said cam surfaces being adapted to engage the adjacent arm to move the corresponding detent out of engagement with the teeth of said cam, and the other of said surfaces being adapted to subsequently engage said projection to impart movement to said bolt.

34. In a lock, a bolt, an actuating member to impart movement to said bolt, a device to be operated comprising a movable part, a plate arranged to be actuated by each operative movement of said actuating member, and directly connected with said movable part to cause the same to be moved away from said actuating member upon each movement of the latter.

35. In a lock, a bolt, an actuating member to impart movement to said bolt, a device to be operated comprising a movable member, a plate arranged in the path of said actuating member and directly connected with said movable member of said device, whereby said plate will be actuated upon each operative movement of said actuating member and said movable member will be caused to move with said plate.

36. In a lock, a bolt, an actuating member therefor, a device to be operated comprising a reciprocatory member, a plate directly connected with said reciprocatory member and arranged in the path of said actuating member, and a guide for said plate, whereby each movement of said actuating member will impart operative movement to said reciprocatory member.

37. In a lock, the combination, with a bolt, and means for actuating said bolt, of an operable device, means controlled by the actuating means for said bolt to actuate said device, and full stroke mechanism to control said device.

38. In a lock, the combination, with a bolt, a movable member, and means for actuating said bolt and said movable member, of an operable device controlled by said actuating means, and full stroke mechanism for said actuating means to prevent said operable device from being successively operated without causing the full operation of said movable member.

39. In a lock, the combination, with a bolt, and an actuating device, of paper feeding mechanism comprising an arm having a cam slot, and a pin connected with said actuating mechanism and extending into said cam slot, said cam slot being of such shape that said arm will receive movement dur-

ing a portion only of the movement of said actuating mechanism.

40. In a lock, the combination, with a bolt, a movable member, an actuating member for said bolt and said movable member, a plate interposed between said actuating member and said movable member, and a plunger supporting said plate, of operable mechanism comprising a rotatable part, a pinion, pawl and ratchet connection between said pinion and said rotatable part, an arm having a toothed rack meshing with said pinion and also having a cam slot, and a pin connected with said plunger and extending into said cam slot, said cam slot being so arranged that during a portion of the movement of said plunger that portion of the slot in which the pin is moving will lie parallel with the path of movement of the pin.

41. In a lock, a frame comprising two members adapted to be supported on opposite sides of a door, devices to detachably connect said members one to the other, a bolt, a bolt-actuating member mounted on one of said frame members, a shaft connected with said bolt-actuating member, a knob mounted on the other of said frame members, and a detachable connection between said knob and said shaft.

42. In a lock, a frame comprising two plates adapted to be supported on opposite sides of a door, devices extending through said door to connect said plates one to the other, a bolt, an actuating member for said bolt mounted on one of said plates, a shaft carried by said plate and connected with said actuating member, a knob, and knob-controlling devices mounted on the other of said members, and a slip connection between said knob and said shaft.

43. In a lock, a reciprocating member having a longitudinal series of teeth, a pawl mounted on a fixed support and arranged to engage said teeth when said reciprocating member is moved from its normal position, and means to disengage said pawl when said reciprocating member has completed its movement.

44. In a lock, a reciprocating member having a longitudinal series of teeth, a pawl mounted on a fixed support and arranged to engage said teeth when said reciprocating member is moved from its normal position, means to disengage said pawl when said reciprocating member has completed its movement, and a device operatively connected with said reciprocating member.

45. In a lock, a reciprocating member having a longitudinal series of teeth, a pawl mounted on a fixed support and arranged to engage said teeth when said reciprocating member is moved from its normal position, means to disengage said pawl when said reciprocating member has completed its movement, and means to hold said pawl

in its inoperative position during the return movement of said reciprocating member.

46. In a lock, a reciprocating member having a longitudinal series of teeth, a pawl mounted on a fixed support and arranged to engage said teeth when said reciprocating member is moved from its normal position, a part connected to and moving with said reciprocating member to move said 10 pawl into its inoperative position as said reciprocating member approaches the end of its movement in one direction, and means supported independently of said reciprocating member to retain said pawl in its in- 15 operative position during the return movement of said reciprocating member.

47. In a lock, a reciprocating member having a longitudinal series of teeth, a pawl mounted on a fixed support and arranged 20 to engage said teeth when said reciprocating member is moved from its normal position, a part connected to and moving with said reciprocating member to move said pawl into its inoperative position as said 25 reciprocating member approaches the end of its movement in one direction, means sup- ported independently of said reciprocating member to retain said pawl in its inoperative position during the return movement 30 of said reciprocating member, and means connected to and moving with said reciprocating member to release said pawl from said last-mentioned means.

48. In a lock, a device to be operated, a reciprocating member connected with said 35 device to impart movement thereto, said reciprocating member having a longitudinal series of teeth, a spring-pressed pawl mounted on a fixed support and arranged to en- 40 gage the teeth of said reciprocating member when said device has begun its operative movement, a part connected to and moving with said reciprocating member to move

said pawl into an inoperative position as 45 said device approaches the end of its opera- tive movement, a spring-pressed dog ar- ranged to engage said pawl and hold the same in its inoperative position during the return movement of said device, and means connected to and movable with said device 50 to engage said dog and move the same into an inoperative position as said platen ap- proaches its normal position.

49. In a full stroke mechanism, the com- bination, with a reciprocating member hav- 55 ing a longitudinal series of teeth, a pawl mounted on a fixed support adjacent to said reciprocating member and arranged to en- gage said teeth when initial movement has been imparted to said member, means con- trolled by the movement of said reciprocating member to disengage said pawl, to re- 60 tain the same in its inoperative position during the return movement of said reciprocating member and to release said pawl 65 when said reciprocating member returns to its normal position.

50. In a lock, the combination with an actuating mechanism, of key-controlled de- 70 vices having a part movable into a locking position relative to said actuating mecha- nism to prevent operative movement from being imparted thereto, and having other parts controlled by the position of the first- 75 mentioned part and coöperating to prevent the removal of the key while said first-mentioned part is in its inoperative position relative to said actuating mechanism.

In testimony whereof, we affix our signatures in presence of two witnesses.

BERNARD H. ZIEHLER.
DON RAY ROWE.
